(57) **CLAIM**

The ornamental design for a visual latching indicator for an electrical bushing and terminator, as shown and described.

DESCRIPTION

FIG. 1 is a perspective view of an electrical bushing and terminator.

FIG. 2 is a front view of the electrical bushing and terminator of FIG. 1.

FIG. 3 is a rear view of the electrical bushing and terminator of FIG. 1.

FIG. 4 is a side view of the electrical bushing and terminator of FIG. 1.

FIG. 5 is a side view of the electrical bushing and terminator of FIG. 1, as seen from the opposite side as that illustrated in FIG. 4.

FIG. 6 is a bottom view of the electrical bushing and terminator of FIG. 1; and,

FIG. 7 is a top view of the electrical bushing and terminator of FIG. 1.
